DESIGN FOR A RUBBER BALL

Clinton J. Davidson, San Diego, Calif.

Application January 22, 1944, Serial No. 112,300

Term of patent 14 years

(Cl. D34—15)

To all whom it may concern:

Be it known that I, Clinton J. Davidson, a citizen of the United States of America, residing at San Diego, in the county of San Diego and State of California, have invented a new, original, and ornamental Design for a Rubber Ball, of which the following is a specification, reference being had to the accompanying drawing, forming part thereof.

Figure 1 is a side elevational view of a rubber ball showing my new design and Fig. 2 is a vertical sectional view.

I claim:

The ornamental design for a rubber ball, substantially as shown.

CLINTON J. DAVIDSON.
